SWEETENING PROCESS

Donald E. Payne, Chicago, and Vanderveer Voorhees, Homewood, Ill., assignors to Standard Oil Company, Chicago, Ill., a corporation of Indiana

Application December 31, 1943, Serial No. 516,368

5 Claims. (Cl. 196—32)

1

This invention relates to a process of sweetening hydrocarbon oils and particularly petroleum distillates such as gasoline and kerosene. The process is especially applicable to the sweetening of cracked products such as gasoline and kerosene from thermal or catalytic cracking processes. One of the objects of the invention is to provide a process of removing mercaptans from gasoline and other light petroleum products by extraction with alkaline solutions. Another object of the invention is to improve the alkaline extraction of mercaptans by employing a new method of regenerating the alkaline solutions which are recycled in the process. Still another object of the invention is to provide a method for producing "sweet" gasoline which will pass the "doctor" test without the use of expensive reagents or re-treating operations. In brief, our invention, which will be described more specifically herein-after, involves the use of a second stage of regeneration for at least a part of the caustic solution used in sweetening, after the solution has been regenerated incompletely in the usual manner, and it involves more particularly the extraction of the partially regenerated caustic with a stream of sweetened distillate from the process itself.

The process of sweetening gasoline involves primarily removal from the gasoline of mercaptans which are dissolved therein in a small amount. It has heretofore been demonstrated that the mercaptans of low molecular weight such as ethyl and propyl mercaptans are relatively easily removed by extraction with alkaline solutions such as caustic soda or caustic potash. The higher molecular weight mercaptans such as amyl and hexyl mercaptans, being more soluble in the oil, are less readily removed by caustic solutions. To facilitate the removal of mercaptans it has heretofore been the practice to add to the caustic solution an organic reagent or solvent commonly called a "solutizer" which is soluble in the caustic, thereby increasing the solubility of the mercaptans in the caustic solution and facilitating their extraction from the gasoline. From 5 to 40% of solutizer is usually effective, and the amount of solution required to sweeten gasoline is usually 2 to 20%, for example 4 to 10% by volume based on gasoline treated.

As the extraction proceeds, for example in a continuous process where the gasoline is passed thru a body of the caustic solution or where the gasoline is continuously extracted in a tower thru which caustic solution is recirculated from a supply, the mercaptan content of the caustic soon

2

increases to a point where mercaptans are no longer completely removed from the gasoline, at least not sufficient to provide a sweet product which will pass the doctor test. This test has long been used in the petroleum industry and consists in shaking a sample of oil with a alkaline solution of sodium plumbite in the presence of a trace of sulfur. If the oil contains an objectionable amount of mercaptan, a colored precipitate of lead mercaptide will be observed.

In order to obtain more complete removal of mercaptans with alkaline solutions, either with or without the addition of organic mercaptan solvents, it is necessary to regenerate the alkaline solution, by which is meant the removal of mercaptans therefrom. This may be accomplished in several ways, one of the most common methods being to heat the solution to an elevated temperature, for example to the boiling point or near boiling point, and vaporize off the mercaptans by a current of air, steam or an inert gas, such as flue gas. This regeneration technique is based on the fact that the alkali mercaptides, for example sodium or potassium mercaptides, contained in the alkaline solution dissociate at higher temperatures as the vapor pressure of the mercaptan in equilibrium therewith increases. By removing the mercaptan vapor, the equilibrium is displaced and the caustic solution may be substantially freed of mercaptans. This solution is then cooled and returned to the gasoline extractor for further use. The mercaptan vapors liberated from such a process may be condensed and the mercaptans recovered, or the vapors may be burned in a furnace.

Another method of regeneration which has certain advantages from the standpoint of saving of heat comprises contacting the mercaptan-containing alkaline solution with air or oxygen or other oxidizing agent at normal temperatures or temperatures only slightly elevated, for example 100 to 130° F. The mercaptans are oxidized by the air in the presence of caustic to organic disulfides which are no longer soluble in the caustic solution and which may be separated therefrom, after which the alkaline solution is returned to the extractor for further use. The oxidation of mercaptans to disulfides is not a very rapid reaction, particularly in the case of the lower molecular weight mercaptans, and therefore it is desirable to employ a catalyst to speed up this reaction. A number of catalysts have been proposed and used heretofore, both organic and inorganic. In the latter class are the salts of lead, copper, cobalt, nickel, cadmium, zinc and vana-

dium, while the organic oxidation catalysts are generally phenolic in character including cresols, amino phenols, and particularly the polyhydroxy aromatic compounds, such as hydroquinone, catechol, pyrogallol, dihydroxynaphthalene and the various tannins. These catalysts are generally effective in amounts of 0.1% up to 2 or 3%.

When using the organic regeneration catalysts, difficulty is sometimes encountered with resinification or overoxidation of the catalyst as a result of long contact with air or oxygen in the regenerator. This may occur, for example, when using tannin as the catalyst in which case it is desirable to avoid regenerating the caustic solution with air to a point where complete regeneration is obtained. As a result, a small amount of mercaptan may be returned to the gasoline extractor and incomplete sweetening of the gasoline follows, owing to the impossibility of completely removing mercaptans from gasoline with a caustic solution which contains mercaptans. Even when not confronted with the problem of regeneration catalyst destruction, there is always some difficulty in producing sweet gasoline by regeneration and recycling alkaline solutions owing to the difficulty of regenerating these solutions to a point where the mercaptan concentration will be sufficiently low to provide the necessary equilibrium for sweet gasoline. In order to pass the doctor test a gasoline must contain less than about .001% of mercaptan sulfur.

In our process we have provided a method of obtaining sweet gasoline by substantially completely removing the mercaptans from at least a part of the caustic solution after the solution has been regenerated in the usual manner and before recycling back to the gasoline extractor. One modification of our process is illustrated by the accompanying drawing which shows diagrammatically an apparatus for carrying out the process.

Referring to the drawing, a hydrocarbon feed stock, for example gasoline which may be cracked or straight-run gasoline, or an absorption naphtha is charged to the process by line 10 leading to pretreating extractor 11 wherein the gasoline is contacted with an alkaline solution introduced at 12. The principal purpose of the pretreatment in 11 is to remove from the gasoline any hydrogen sulfide it may contain and other acidic materials such as naphthenic acids and phenols. On account of their high oil solubility the phenols are not completely removed by alkaline washing but their concentration is reduced to a point where they do not interfere with subsequent operation of the process. For this purpose we may use caustic soda, caustic potash, sodium carbonate, or other convenient alkaline material. When washing cracked gasoline, a sodium hydroxide solution of 5 to 30%, for example 20%, is satisfactory. The caustic for the purpose may be stored in supply tank 13 and recycled thru lines 12 and 14. Additional caustic may be supplied to the system by line 15 and spent caustic may be withdrawn by line 16. The spent caustic solution, which may contain acids and phenols dissolved therein in an amount of about 10 to 40%, preferably 25 to 30%, may be acidified subsequently to recover phenols which are of value as insecticides and wood preserving agents.

The washed gasoline from pretreater 11 is conducted by line 17 to the main mercaptan extractor 18. Tower 18 may be provided with suitable baffle plates or packed with broken tile, Raschig rings, Berl saddles, or other suitable contacting

material. As the gasoline flows upward thru the tower 18 it encounters streams of caustic solution introduced at 19, 20 and 21 before it passes out at the top of the tower thru line 22 sufficiently depleted of mercaptans to meet the desired specifications. The amount of caustic solution can be about 5 to 15%, for example. For the purpose of our process, caustic solutions containing from about 10 to 30% are preferred, but other concentrations may be used, e. g. 5 to 40%, an example of a suitable concentration being 20%. In general caustic potash is somewhat more effective for mercaptan removal than caustic soda. The caustic solution is withdrawn from the base of the extractor by line 23 and conducted thru heater 24 to regenerator 25. Tower 25 may also be a baffled or packed tower, or a mechanically agitated vessel, in which the caustic solution is contacted with a current of air introduced at 26 and vented at 27. At the base of the tower the solution is drawn into settling section 28 where disulfides are allowed to separate and are withdrawn by line 29. Gas oil or other low volatile solvent may be introduced into separator 28 to assist in removal of disulfides. Catalyst for regeneration which may consist of an aqueous or alkaline solution of catechol or tannin is introduced by line 30 in the desired amount. After having once been brought up to the desired concentration it is not necessary to add additional catalyst except at infrequent intervals to make up for mechanical losses due to leakage and entrainment and slight losses from chemical destruction of the catalyst due to side reactions.

The partially regenerated caustic solution, which may be regenerated, for example, to the extent of 90 to 98%, is withdrawn by line 31 and recycled thru cooler 32 and line 19 to the extractor. It is preferred to operate the extractor at ordinary temperature, for example 30 to 50° in winter and up to 70 or 90° in summer, while the caustic regenerator 25 is preferably operated at a temperature of around 120 to 130° F., although a temperature of 150° F. may be used. We may operate our regenerator at the same temperature as the mercaptan extractor, however. Inasmuch as the partially regenerated caustic in line 19 contains mercaptans, it will not produce a sweet gasoline at that point in the extractor but serves to remove the bulk of the mercaptans in the gasoline and leave therein only a small residual amount. In order to reduce the mercaptan concentration still further, we withdraw a portion of the partially regenerated caustic solution by line 33 and conduct it to caustic purifier 34 where it is extracted by a stream of sweet gasoline withdrawn from line 22 by line 35 leading thru heat exchanger 36 and heater 36a. The amount of gasoline withdrawn to purifier 34 may be about 10 to 50% of the gasoline charged to extractor 18, preferably about 20 to 30%. In purifier 34 the small amount of mercaptans remaining in the caustic are transferred counter-currently to the gasoline which is then conducted by line 37 back thru exchanger 36 and cooler 36b to an intermediate point in the extractor 18. The purified caustic solution now substantially free of mercaptans is conducted by line 38 thru cooler 39 and line 20 back to the extractor, introducing it at a point substantially above the point of introduction of the partially regenerated caustic solution previously introduced at 19. The upper section of the extractor therefore forms a second extraction zone and if desired, separate towers may be used for the purpose. In case separate towers are

used, it is preferred to conduct the alkaline solution from the bottom of the second extraction zone to the top of the first extraction zone but it may also be conducted directly back to the regenerator 25.

In operating our process, we prefer to maintain the temperature of the caustic purifier 34 above the temperature of the extractor 18 in order to obtain a favorable equilibrium for transfer of mercaptans from gasoline to caustic in 18 and caustic to gasoline in 34. For this purpose, a temperature differential of about 25 to 150° F. is usually sufficient, preferably about 100° F. The caustic purifier 34 may be operated, if desired, at temperatures in the range of 150 to 225° F. in order to obtain more complete removal of mercaptans from the caustic solution. For this purpose suitable heating coils may be supplied in 34 and the caustic solution in line 33 may be diverted thru heater 40. When the temperature is above the boiling point of the distillate, pressure will be needed.

The proportion of the caustic solution in line 31 which is diverted thru line 33 for the purpose of completing the sweetening at the top of extractor 18 does not need to be rigidly defined as there is considerable flexibility in the operation of our process. Thus when a fairly complete regeneration of caustic solution is obtained in 25, we may divert only 5 or 10% of the caustic solution thru purifier 34. Under other conditions, we may divert 35 to 50% of the caustic solution thru the purifier and we may even operate with all the caustic solution being conducted thru the purifier 34, depending on the economics of the operation, a factor affected by many variables. In general we prefer to divert about 10 to 25% of the caustic thru the purifier.

On account of unavoidable contamination it is sometimes desirable to withdraw caustic solution from the system and replace it with fresh caustic, and this may be done by line 41 and discharge valve 42. If desired, the caustic removed from the system in this way may be employed in the pretreating system by conducting it thru valve 43. Fresh caustic supplied thru line 21 may be of the same strength as that used in the system or it may have a higher strength if it is desired to build up the concentration of the caustic in the system.

By introducing the fresh caustic at a point above the point of introduction of regenerated caustic thru line 20 we obtain additional extraction of mercaptans by means of caustic solution which is entirely free of mercaptans, thus providing a still more favorable equilibrium for mercaptan removal than that obtained at the lower levels in the extractor 18 by solutions introduced at 19 and 20. If desired, a portion of the caustic solution regenerated in 25 may be completely stripped of mercaptans by steaming, in apparatus not shown, and this solution may be continuously supplied to the extractor by line 21 in order to maintain the desired differential in mercaptan concentration required in the process. When operating in this way, extractor 18 and caustic purifier 34 may be operated at the same temperature, eliminating the need for heat exchangers, heaters and coolers.

As indicated above, we may employ various organic reagents or solvents in the alkaline solution to increase the solubility of mercaptans therein. Examples of such solvents are the phenols and alkyl phenols, cresols, ethyl and propyl phenols, xylenols, organic acids, naphthenic acids, fatty

acids, preferably of 3 to 6 carbon atoms, furoic acid, alcohols, preferably those of low volatility such as glycol and glycerine, ethanol and propanol amine, and the alkyl substituted benzoic acids. 5 The solvents are usually effective in concentrations of about 5 to 50%, depending on solubility and on the character of the solvent. Phenols contained naturally in gasoline, particularly cracked gasoline, may be permitted to collect in the caustic alkali solution to an effective amount, e. g. 10 to 10 25%, and the amount may be controlled by adding phenols recovered from gasoline or by regulating the amount of phenols removed in the pre-wash stage. The extracting solution can be prepared for example by starting with an approximately 30% caustic soda solution and operating on an alkyl phenol containing charging stock such as a cracked gasoline until about 2 mols of the caustic have been converted to sodium phenolate or 15 cresylates, giving a washing solution containing about 20-25% of phenolates and 20% free caustic. The addition of about 1% of catechol, hydroquinone, or tannin to this solution is sufficient to enable it to be regenerated and recycled almost 20 indefinitely, make-up being necessary only for 25 mechanical losses.

Having thus described our invention what we claim is:

1. The process of sweetening mercaptan-containing petroleum distillates which comprises contacting said distillates countercurrently in a first extraction zone with an aqueous caustic alkali solution containing a solutizer for mercaptans, separating said caustic alkali solution and dissolved mercaptans from partially sweetened distillate and contacting it with air in a first regeneration stage in the presence of a phenolic mercaptan oxidation catalyst, thereby partially regenerating the solution by oxidation, controlling the oxidation to convert a major proportion but not all of said mercaptans to organic disulfides insoluble in said caustic solution while avoiding destruction of said phenolic oxidation catalyst by excessive oxidation, recycling a portion of said partially regenerated caustic solution to said first extraction zone and contacting it with petroleum distillate to remove mercaptans from additional amounts of distillate supplied thereto, countercurrently contacting another portion of said partially regenerated caustic solution in a second regeneration stage with a stream of sweet distillate produced in the process, the volume of which is substantially less than the volume of mercaptan-containing distillate undergoing treatment, thereby transferring residual mercaptans from said partially regenerated caustic solution to said distillate stream and producing a completely regenerated caustic solution, separating said distillate and caustic solution in said second regeneration stage, recycling the separated distillate stream to said first extraction zone and combining it therein with the mercaptan-containing distillate first mentioned, countercurrently contacting in a second extraction zone said completely regenerated caustic solution with said partially sweetened distillate from said first extraction zone, thereby producing a sweet distillate product, separating said product from caustic alkali solution in said second extraction zone and transferring the last-mentioned solution to said first extraction zone wherein it is contacted with said mercaptan-containing distillate first mentioned.
2. The process of claim 1 wherein the second regeneration stage is operated at a higher tem-

perature than the temperature of said distillate extraction zones.

3. The process of claim 1 wherein hydrogen sulfide, phenols and organic acids are separated from the distillate charged to said first extraction zone by initially contacting it with an alkaline solution.

4. The process of sweetening a petroleum distillate which comprises contacting a continuous stream of said distillate with an aqueous caustic alkali solution in two successive extraction zones, partially sweetening said distillate in the first of said extraction zones wherein mercaptans are dissolved in said alkali solution, separating mercaptan-containing alkali solution from distillate in said first extraction zone and subjecting it to oxidation by contacting with oxygen in a first regeneration zone at a temperature of about 120 to 150° F., regulating the extent of oxidation to convert a major part of the dissolved mercaptans in said solution to disulfides while retaining a minor part of the mercaptans unoxidized, separating disulfides in said first regeneration zone and discarding them from the system, recycling a part of the partially regenerated alkali solution from said first regeneration zone to said first extraction zone for extraction therein of additional amounts of sour distillate, transferring another part of the partially regenerated alkali solution from said first regeneration zone to a second regeneration zone wherein substantially all remaining mercaptans are removed by countercurrent contacting in the absence of oxygen with a substantially mercaptan-free liquid hydrocarbon stream, thereby transferring mercaptans from said solution to said hydrocarbon stream, the resulting hydrocarbon stream containing mercaptans being then charged to said first extraction zone for further removal of mercaptans therein, conducting regenerated alkali solution from said second regeneration zone to the second of said distillate extraction zones, and contacting it therein with partially sweetened distillate from said first extraction zone, thereby completely sweetening said distillate, separating alkali solution from distillate in said second extraction zone and combining it with the alkali solution in said first extraction zone for the removal of mercaptans from said additional amounts of sour distillate therein.

5. The process of sweetening a petroleum distillate which comprises contacting a continuous stream of said distillate with an aqueous caustic alkali solution in two successive extraction zones, partially sweetening said distillate in the first of said extraction zones wherein mercaptans are dissolved in said alkali solution, separating mercaptan-containing alkali solution from distillate

in said first extraction zone and subjecting it to oxidation by contacting with oxygen in a first regeneration zone at a temperature of about 120 to 150° F., regulating the extent of oxidation to convert a major part of the dissolved mercaptans in said solution to disulfides while retaining a minor part of the mercaptans unoxidized, separating disulfides in said first regeneration zone and discarding them from the system, recycling a part of the partially regenerated alkali solution from said first regeneration zone to said first extraction zone for extraction therein of additional amounts of sour distillate, transferring another part of the partially regenerated alkali solution from said first regeneration zone to a second regeneration zone wherein substantially all remaining mercaptans are removed by extraction in the absence of oxygen with a hydrocarbon substantially free of mercaptans, conducting regenerated alkali solution from said second regeneration zone to the second of said distillate extraction zones, and contacting it therein with partially sweetened distillate from said first extraction zone, thereby completely sweetening said distillate, separating alkali solution from distillate in said second extraction zone, combining it with the alkali solution in said first extraction zone for the removal of mercaptans from said additional amounts of sour distillate therein, and employing a portion of the completely sweetened distillate from said second extraction zone as the mercaptan-free hydrocarbon for extracting the alkali solution in said second regeneration zone, thereby transferring mercaptans from said solution to said sweetened distillate and charging the resulting distillate containing mercaptans to said first extraction zone.
